(57) **CLAIM**

The ornamental design for a triangular curvilinear spa shell with steps, as shown and described.

DESCRIPTION

This application is related to U.S. application Ser. No. 29/218,268, filed on the same day as this application, and entitled “triangular curvilinear spa shell”.

FIG. 1 is a perspective view of the triangular curvilinear spa shell with steps.

FIG. 2 is a top view of the triangular curvilinear spa shell with steps.

FIG. 3 is a rear-view of the triangular curvilinear spa shell with steps.

FIG. 4 is a front-view of the triangular curvilinear spa shell with steps; and,

FIG. 5 is a side view of the triangular curvilinear spa shell with steps.

The broken lines are for illustrative purposes only and form no part of the claimed design.
